UNITED STATES PATENT OFFICE.

EDWARD W. FONDA, OF ATHENS, MICHIGAN.

WAGON-BOX.

SPECIFICATION forming part of Letters Patent No. 646,492, dated April 3, 1900.

Application filed April 17, 1899. Serial No. 713,305. (No model.)

To all whom it may concern:

Be it known that I, EDWARD W. FONDA, a citizen of the United States, residing at Athens, in the county of Calhoun and State of Michigan, have invented certain new and useful Improvements in Wagon-Boxes, of which the following is a specification, reference being had therein to the accompanying drawings.

10 My invention relates to an attachment for wagon-boxes; and it consists of an improved form of "tail-board" and means for readily attaching and operating the same.

15 The object of my invention is to provide ready means for unloading the box of its contents expeditiously and with safety to the product being handled.

20 In explanation, an ordinary wagon-box mounted with the usual side-boards and loaded with farm produce—such as apples, potatoes, &c.—cannot be unloaded directly with a scoop-shovel; but a part of the load must first be slowly and laboriously removed by hand before a shoveling start can be secured. To obviate this difficulty and provide

25 means for at once placing the shovel in operation, I have devised the tail-board herein described and illustrated, which can be readily attached to any regular box.

30 I have illustrated my invention in the accompanying drawings, in which—

Figure 1 is a perspective view of a wagon-box having my improved form of tail-board in closed position. Fig. 2 is a like view of

the same with the tail-board dropped back in 35 position for unloading.

Like letters refer to like parts in both drawings, in which—

A represents the wagon-box; B, my improved tail-board; C, the auxiliary side-boards; d, the narrow box-boards; e e, the tail-board hooks; f g, the staples for engaging the same; h, tail-board rod-brackets; i, tail-rod; j, tail-board lugs, and k the hook-bracket bar.

45 The tail-board is held in position by the rod i, inclosing the lugs j j, at its foot or lower end, and at its top by the retaining-hooks e e, which when relaxed to the staples g form an inclined plane of the same, upon which the 50 operator may stand and against the downwardly-inclined surface of which the scoop may be used to remove the initial part of the contained but relaxed load.

Having thus fully described my invention, 55 what I claim as new, and desire to secure by Letters Patent of the United States, is—

The combination with a wagon-box, of an adjustable tail-board, supported at its foot by retaining lugs and rod, and at its top by 60 side hooks and staples, substantially as shown and described.

In testimony whereof I affix my signature in presence of two witnesses.

EDWARD W. FONDA.
